UNITED STATES PATENT OFFICE.

CARL LAWRENCE MATTISON, OF ROCKFORD, ILLINOIS, ASSIGNOR TO MATTISON MACHINE WORKS, OF ROCKFORD, ILLINOIS, A CORPORATION OF ILLINOIS.

ABRADING OR POLISHING MACHINE.

Application filed September 23, 1921. Serial No. 502,612

To all whom it may concern:

Be it known that I, CARL LAWRENCE MATTISON, a citizen of the United States, residing at Rockford, in the county of Winnebago and State of Illinois, have invented certain new and useful Improvements in Abrading or Polishing Machines, of which the following is a specification.

My invention relates to abrading machines or polishing machines, and refers more particularly to that type in which an endless abrading belt or polishing belt is applied to the work to be treated by means of a reciprocating shoe structure which bears upon one run of the traveling belt.

The invention of this application may be considered as covering improvements in the construction and arrangement disclosed in my co-pending application Serial No. 490,290, filed August 8, 1921. In the structure of this co-pending application provision is made to unclutch the shoe structure from the reciprocating band to permit manual application of the shoe structure against the abrading belt. In this arrangement, however, the entire shoe structure together with the supporting rail and the rail supporting mechanism must be moved in manually applying pressure against the belt.

The general object of my present invention is to eliminate all unnecessary weight and resistance, and to produce a construction, arrangement and operation which will permit manual adjustment of the pressure to be accomplished with greater ease, precision and efficiency. More in detail, the main object of my invention is to provide a shoe structure movable as a whole on a vertically movable rail but having a comparatively light shoe part movable independently of the rail to be readily and accurately applied by hand with the desired pressure engagement against the abrading belt.

My improved shoe structure comprises a main part or carriage which receives the rail, and a comparatively light shoe part, and another important object of my invention is to provide improved means for suspending said shoe part below the carriage part for vertical reciprocation relative thereto.

Another important object of my invention is to provide a clutch member on the shoe part for connecting the shoe structure with a traveling member, together with means for

operating the clutch member and controlling the vertical reciprocation of the shoe part.

Another important object of the invention is to provide a hand lever on the shoe structure connected with the clutch member and the shoe part to control the operation and adjustment thereof.

Another important object of the invention is to produce improved means for locking the various parts in normal position when the shoe structure is being automatically reciprocated.

In the accompanying drawings I have shown by way of example a machine which represents the preferred embodiment of my invention but it should be understood that the following detailed description of this particular embodiment is given only for the sake of imparting an understanding of the invention, and that I do not intend to limit the invention to the construction herein disclosed but aim to cover all modifications, equivalent and alternative constructions falling within the scope of the appended claims.

In the accompanying drawings Figure 1 is a front elevational view of a machine to which my improvements are applied.

Fig. 2 is a plan view.

Fig. 3 is an enlarged front elevational view of the shoe structure.

Fig. 4 is an enlarged side elevational view of the shoe structure with the carriage frame broken away at plane 4-4, Fig. 3.

Fig. 5 is an enlarged sectional view on plane 5-5, Fig. 1.

Fig. 6 is an enlarged sectional view on plane 6-6, Fig. 1.

Fig. 7 is a sectional view on plane 7-7, Fig. 3.

Fig. 8 is a view similar to Fig. 4, showing the controlling lever in lower position, and

Fig. 9 is a sectional view on plane 9-9, Fig. 7.

The general arrangement of the machine being the same as that of the co-pending application referred to, I will here give only a brief description.

The supporting base structure comprises the pedestals 1 and the top 2, the brackets 3 vertically slidable on the pedestals having the rails 4 on which the work supporting platform 5 is reciprocable transversely of the base structure below the top thereof. At the left end of the base structure is the trans-

versely extending drive shaft 6, driven through gearing 7 by the motor 8, the shaft having the pulley 9 at its front end over which travels the abrading belt 10, which 5 also passes over the pulley 11 at the right end of the machine, said pulley being on the transverse shaft 12 which is bodily adjustable by means of suitable mechanism 13.

At its rear end the driving shaft 6 has 10 the pulley 14 connected by belt 15 with the pulley 16 on the counter-shaft 17. The shaft 17 transmits rotation to the shaft 19 through the gearing 18, and by means of suitable clutch mechanism 20 controlled by lever 20'. 15 This shaft is connected with the crank shaft 21 either through the gearing 22 or the gearing 23. At its rear end the shaft 21 has the crank disk 24 having the crank pin 25 which is connected by the connecting rod 26 20 with the gear sector 27 at the left end of the machine, there being a similar sector 28 at the right end of the machine, the sectors being connected together by the connecting rod structure 29. The sector 27 is secured on 25 the rear end of the shaft 29 journaled in the frame 30, and in said frame below said shaft is journaled the shaft 31 which at its rear end carries the pinion 32 meshing with the gear sector 27, the shaft 31 at its front end 30 supporting the disk 33. The sector 28 is secured on the rear end of the shaft 34 in the bearing frame 35 which frame also journals the shaft 36 having the gear pinion 37 thereon meshing with the sector 28, the shaft 36 at its front end supporting the disk 38. Stretching between the disks and secured thereto is the band 39 which has clamped thereto the abutment frame 39' by means 35 of which the shoe structure S may be connected with the band to be reciprocated therewith. The reciprocation of the band is caused by the gear sectors which are oscillated by their connection with the crank mechanism 24, 25.

45 The supporting mechanism for the shoe structure is clearly shown in Figs. 1, 2, 5 and 6. A number of brackets 40 secured on the machine top 2 support upper and lower rods 41 and 42. In front of these rods and 50 parallel therewith are the rods 43 and 44 connected by vertical links 45. Horizontal links 46 connect the rods 41 and 43 and horizontal links 47 connect the rods 42 and 44. The front links 45 have L-shaped extensions 55 48 which at their front ends are secured to a rail beam 49 of I cross section and extending lengthwise of the machine at the front thereof and above the lower run of the abrading belt.

60 On this rail beam the shoe structure is reciprocated. To balance the weight of the rail beam and shoe structure thereon, counterweights 50 are provided, these weights being adjustably secured on the stem 51 of the 65 horizontal links 52 detachably engaging the

upper rods 41 and 43 as clearly shown in Fig. 5. By virtue of the parallel link suspension the beam 49 will always be in a vertical plane during up and down movements thereof. 70

The shoe structure comprises a carriage part C and a shoe part S. The carriage frame of the shoe structure is of C shape cross section in order that it may span the rail 49 and clear the rail supporting brackets 75 48 which are extensions of the lower ends of links 45. At its upper corners the frame has the extensions 53 forming housing for the upper rollers 54, these rollers engaging on the upper side of the beam. At its lower corners the frame has the housing extensions 80 55 for journaling the rollers 56 which engage with the underside of the rail beam. At the rear of the frame and at the opposite sides thereof are the housing extensions 85 57 and 58 in which are journaled the rollers 59 and 60 for engaging respectively with the sides of the upper and lower flanges of the rail beam. At the front of the frame are the housings 61 and 62 for journaling the 90 rollers 63 and 64 for engaging with the sides of the beam flanges at the front thereof. The carriage can thus freely roll along the rail beam.

Between the lower roller housings 55 of 95 the carriage frame the block 65 of the shoe part S extends transversely and from the front end of this block an arm 66 extends upwardly in front of the carriage and has the shaft 67 in its upper end for pivoting the horizontal links 68 and 69 which engage on either side of the arm and extend rearwardly. At the rear end these links pivot on the shaft 70 secured in the bracket 71 on the carriage frame between the upper 100 roller housings 53. Vertically below the shaft 70 and extending rearwardly from the housing extensions 55 are the threaded lugs 72 and 73 (Fig. 9) which receive the pivot screws 74 and 75 on which are pivoted at the rear ends the links 76 and 77, these links engaging between the blocks 65 and the inner sides of the housing extensions 55. Vertically below the shaft 67 the links 76 and 77 are pivoted by screws 78 115 and 79 to the block 65 at the sides thereof. The links 76 and 77 extend a distance toward each other and then forwardly as clearly shown in Fig. 9 to form the opposed walls 80 and 81 which have the longitudinally extending slots 82 and 83 through which extends the bolt 84. Between the walls 80 and 81 are the spaced apart cam wings 85 and 86 which extend from the head 87 of the operating lever 120 88, the bolt passing through the wings and serving as a pivot for the lever structure. The block 65 has the transversely extending passageway 89 (Fig. 7) in which the bar 90 is reciprocable, the bar at its 130

5 rear end having the upper and lower fingers 91 and 92 for co-operating with the clamp 39' to clutch the shoe structure to the reciprocating band 39. Secured to the front end of the bar by suitable coupling or connecting mechanism 93 is the extension 94 which fits in between the cam wings 85 and 86 of the lever structure. The extension at its outer end is enlarged 10 and has the arcuate slot 95 whose radius center is the axis of the pivot screws 74 and 75, the slot receiving the bolt 84.

15 Extending downwardly from the block 65 are the front and rear lugs 96 and 97 which support the trunnion screws 98 and 99 which engage with the piece 100. At its opposite sides this piece is engaged by the trunnion screws 101 and 102 which are supported in the lugs 103 and 104 extending 20 upwardly from the shoe 105, the shoe having thus universal pivot connection with the block 65 so that it can freely and accurately engage against the top of the abrading belt 100 to accurately hold this belt 25 against work to be surfaced. Compression springs 106 are interposed between the shoe and the block 65 which tend to keep the shoe uniformly pressed against the belt, the springs together with the universal pivot 30 connection permitting the shoe to easily give when irregularities are encountered in the surface to be treated, thus avoiding strain in the shoe structure. The shoe detachably supports the shoe plate 107 to 35 which anti-friction facing material 108 may be secured by means of clamp mechanism 109.

40 The shoe structure as a whole is supported on the rail beam 49 which beam can be raised and lowered to raise or lower the shoe structure as a whole, the beam being always in a vertical plane by virtue of the parallel link connection thereof with the supporting brackets 40. The counter- 45 weights 50 are adjusted to tend to hold the beam with the shoe structure thereon up with the shoe plate out of pressure engagement with the abrading belt. By means of the operating lever 110 the beam with the shoe structure may be readily moved downwardly to bring the shoe into pressure engagement with the abrading belt and the surface to be treated. This operating lever mechanism is fully disclosed in the co- 50 pending application referred to. The lever is mounted on the machine frame at 111 to swing vertically and shift longitudinally, and in front of this support it passes through a fitting 112 secured to the upper rod 43 of the link supporting mechanism so that when the lever is raised and lowered by its handle 113 the rail beam will be raised and lowered to adjust the pressure of the shoe structure on the work.

55 60 65 The operating lever 110 is used to control

the pressure when the shoe structure is clutched to the reciprocating band. It is, however, frequently desirable to reciprocate the shoe structure by hand, independently of the band, and to press it against the abrading belt to give extra treatment to work at certain parts. In the arrangement of the co-pending application referred to it is necessary to raise and lower the entire shoe structure together with the rail beam and link mechanism when adjusting for pressure during manual reciprocation of the shoe structure. In my improved construction already described herein it is necessary only to move the shoe part comprising the block 65 with the shoe 105 thereon, the rail beam and carriage part remaining stationary during pressure application of the shoe part to the belt. By swinging the hand lever 88 the shoe structure can first be unclutched from the reciprocating band and then the block 65 with the shoe suspended therefrom may be moved independently in vertical direction to bring the shoe plate into engagement with the abrading belt under the desired pressure. In Figs. 3, 4 and 5 the lever is shown in its normal position, the hand receiving knob 114 being in position over the links 68 and 69. Coiled springs 115 encircling the shaft 70 are secured at one end to the shaft and at their other ends bear against pins 116 on the upper links 68 and 69, these springs tending to hold the arm 66 with the shoe part thereon in upper position with the lower links 76 and 77 abutting 100 against the underside of the carriage frame as clearly shown in Fig. 3. When the lever 88 is in normal position the flat surfaces 117 on the cam wings 85 and 86 will be in abutment against the shoulders 118 at the outer ends of the walls 80 and 81, this engagement holding the lever in its normal position. To assist in holding the block 65 in its normal upper position balls 119 may be provided and held in the pockets 120 in the cam wings 110 and pressed therein by the springs 121 which are held under compression by the screws 122 which thread through the lugs 123 formed on the walls 80 and 81. When the lever 88 was swung into normal position 115 the bolt 84 engaging in the slot 95 caused the bar 90 to be shifted rearwardly to bring the fingers 91 and 92 into clutching engagement with the clamp 39' on the reciprocating band so that when the lever is in 120 normal position the shoe structure will reciprocate with the band. When it is desired to unclutch the shoe structure from the reciprocating band the lever 80 is swung downwardly to the intermediate position 125 shown in Fig. 7, until the flat surfaces 124 on the cam wings come into engagement with the shoulders 125 formed at the rear ends of the walls 80 and 81 (Fig. 9) and such engagement locks the lever in its inter- 130

mediate position. During downward swing of the lever the eccentric cam surface 126 of the cam wings engaged with the shoulders 125 and shifted the bolt 84 forwardly 5 in the slots 82 and 83 in the walls 80 and 81 with the result that the bar 90 was drawn forwardly to withdraw the fingers 91 and 92 from the clamp 39' on the reciprocating band. The shoe structure is now free to be 10 reciprocated manually, and upon further downward movement of the lever 88 the shoe plate may be brought with the desired pressure against the abrading belt. As the lever is swung downwardly the links supporting the block 65 will rotate on their shafts 70 and screws 74 and 75 against the force of the springs 115. During such 15 downward swing the bolt 84 travels through the arcuate slot 95 without disturbing the setting of the clutch bar 90. The weight of the lever 88 will counterbalance to some extent the upward exertion of the springs 115 so that very little effort is required to shift the block 65 with the shoe thereon, and the 20 desired pressure can be applied with precision and accuracy against the abrading belt and thus to the surface to be abraded. The extent of vertical movement of the block 65 is controlled by the extent of the 25 slot 95.

When it is desired to reclutch the shoe structure for automatic reciprocation the lever 88 is raised and the eccentric cam surfaces 127 of the cam wings will then abut 30 against the shoulders 118 to cause the bolt 84 to be shifted rearwardly against the extension 94 so that the bar 90 will be shifted rearwardly to bring the fingers 91 and 92 into clutching engagement with the clamp 39' on the reciprocating band. The knob 114 is on the end of a pin 128 extending at right angles to the lever body and rotatable in the ends thereof so that the knob may turn when clutched in the hand as the shoe 40 structure is reciprocated. Thus by merely swinging down the lever 88 the shoe structure is first unclutched from the reciprocating band and then the comparatively light lower portion of the shoe structure may be 45 independently raised and lowered to adjust with precision and accuracy the pressure engagement of the abrading belt against the surface of the work under treatment.

Briefly summing up the operation of the 50 machine, the operator places a piece of work *W* on the platform 5 and then vertically adjusts the platform to bring the work in proper position relative to the abrading belt. The motor 8 is then started 55 whereupon the belt 10 is propelled. By then operating the clutch lever 20' the crank mechanism is set in operation to cause oscillation of the gear sectors which control the oscillation of the band 39. If it 60 is desired to automatically reciprocate the

shoe structure the lever 88 is swung into its upper position as shown in Figs. 3, 4 and 5 to bring the fingers 91 and 92 into clutching co-operation with the clamp 39' on the band. The shoe structure will now be automatically shifted back and forth on the abrading belt and means of the lever 110 the rail beam with the shoe structure thereon is moved downwardly to bring the shoe with the desired pressure against the belt and the work thereunder. The platform 5 being mounted on rollers it can be readily moved to bring the work thereon into desired position relative to the belt. The downward movement of the rail beam 70 is limited by means of an adjustable jack screw 129 (Fig. 6) which is supported on the arm 130 extending from the frame 2, the jack screw being below the upper outer rod 43 which forms part of the parallel link 75 mechanism, this rod abutting against the jack screw to limit further downward movement of the rail beam and the shoe structure thereon.

The parallel link mechanism and the carriage and shoe structure are exactly counterbalanced by the weights 50 so that the position of the lever 110 governs the effect of the counterweights on the shoe, that is to say, when the lever 110 is in its rearmost position the counterweights will overbalance the shoe and its supporting structure and raise the shoe off from the belt and when the lever 110 is drawn forwardly its weight 80 will cause the carriage and shoe structure to overbalance the weights 50 and descend into engagement with the belt. When the operator desires to manually shift the shoe structure along the rail beam 49 he first moves the hand lever 110 to its rearmost position whereupon the counterweights 50 descend and raise the rail beam 49 to its uppermost position wherein the shaft 43 abuts against a stationary part on the machine frame, in this instance a collar surrounding the shaft 21. The operator then grasps the handle 114 and swings the lever 88 down to the intermediate position shown 85 in Fig. 7. This movement as before explained, causes the bar 90 and the shoe part to be shifted forwardly to withdraw the fingers 91 and 92 from the path of the clamp 39' on the reciprocating band. The shoe structure being now free of the band, the operator may reciprocate the carriage 90 and shoe along the rail beam 49 and may also move the lever 88 downwardly to the extent permitted by the arcuate slot during which movement the shoe part S only 95 will move, the carriage part being vertically stationary since the rail beam is held against upward movement as above explained. The coiled springs 115 will resist downward movement of the shoe part but the force of the springs being in greater part 100

counterbalanced by the weight of the lever structure 88 the operator can with ease and precision vertically move the shoe part to obtain the desired pressure against the belt 5 and the work thereunder. During such vertical movement of the shoe part the roller supported carriage part can be readily shifted along the rail beam by lateral pressure on the lever 88 to bring 10 the shoe part into the desired position with reference to the work. The freedom of movement of the comparatively light shoe part entirely independently of any other part of the machine permits accurate and 15 fine work to be easily and quickly accomplished.

To bring the shoe structure back into its position of automatic reciprocation the operator swings the lever 88 up and back 20 to its normal position. During such movement the shoe part is first raised into position against the carriage and then the clutch bar 90 is shifted rearwardly to engage its clutch fingers between the spaced 25 projections of the clamp 39' on the reciprocating band, and then the lever 110 is operated to control the pressure on the work. The engagement of the flat surfaces of the cam wings against the abutment shoulders 30 provided therefor will hold the lever 88 in its upper position against accidental displacement, and the balls 119 which are spring pressed against the cam wings will assist the coiled springs 115 in holding the 35 shoe part and the lever 88 in normal position.

I claim as my invention:

1. A machine of the class described having in combination, a traveling member, a 40 shoe structure comprising a carriage part and a shoe part, a rail support for receiving the carriage part, means operable for connecting said shoe structure with said traveling member to travel therewith, and 45 for disconnecting said shoe structure from said traveling member, said means being operable also for vertically-shifting said shoe part independently of said carriage part.

2. A machine of the class described having in combination, a traveling member, a 50 shoe structure comprising a carriage part and a shoe part, a rail receiving the carriage part, clutch mechanism for connecting said shoe structure with said traveling member 55 and for disconnecting it therefrom, said shoe part being vertically adjustable relative to said carriage part, and a common operating lever for controlling the clutch mechanism and the adjustment of said shoe 60 part.

3. A machine of the class described having in combination, a traveling member, a shoe structure comprising a carriage part and a shoe part, said shoe part being 65 suspended from said carriage part and

adapted for vertical movement relative thereto, a rail receiving said carriage part, clutch mechanism for connecting said shoe structure with said traveling member, and for disconnecting it therefrom, and means 70 on said shoe part for controlling said clutch mechanism and for moving said shoe part independently of said carriage part.

4. In a machine of the class described, the combination of a traveling member, a 75 shoe structure comprising a carriage part and a shoe part, said shoe part being adapted for vertical movement relative to said carriage part, a rail receiving said carriage part whereby said shoe structure may be 80 shifted as a whole, clutch mechanism on said shoe part for connecting said shoe structure with said traveling member to travel therewith, means for operating said clutch mechanism, and means for adjusting said 85 shoe part.

5. In a machine of the class described, the combination of a traveling member, a shoe structure comprising a carriage part and a shoe part, a rail receiving the carriage 90 part on which the shoe structure may travel as a whole, said shoe part being vertically adjustable on said carriage part, clutch mechanism on said shoe part for connecting said shoe structure with said traveling 95 member to travel therewith, and common means for operating said clutch mechanism and for adjusting said shoe part.

6. In a machine of the class described, the combination of a reciprocatory shoe 100 structure comprising upper and lower parts, a reciprocatory driver, parallel link structures suspending said lower part of the shoe structure from the upper part thereof, a lever hinged on said link structure by 105 means of which said structure may be actuated to raise and lower the lower part of the shoe structure, a clutch member for connecting the shoe structure with the reciprocatory driver, and a connection between 110 said lever and clutch mechanism whereby said lever forms a means for operating said clutch mechanism.

7. In a machine of the class described, the combination of a reciprocatory shoe 115 structure comprising an upper part and a lower part, a frame pivoted to said parts and adapted to be swung to move said lower part vertically with reference to the upper part, a handle for said frame, a clutch member on said shoe structure, and a connection between said shoe structure and handle whereby operation of said handle to swing said frame will also operate said clutch 120 member.

8. In a machine of the class described, the combination of a reciprocatory shoe 125 structure comprising an upper part and a lower part, a frame hinged to said upper and lower parts and adapted to swing to 130

- move said lower part vertically, a clutch member shiftable transversely on said lower part, a handle hinged on said frame to swing thereon, a connection between said clutch member and handle, said handle when swung causing operation of said clutch member and serving also as a means for swinging said frame to adjust said lower part of the shoe structure.
10. In a machine of the class described, the combination of a reciprocatory driver having a clutch member thereon, a reciprocatory shoe structure, the lower part of said shoe structure being movable vertically relative to the upper part thereof, a clutch member shiftable on said lower part to be brought into or out of operation with said driving clutch member, and means for vertically adjusting said lower part when said clutch members are disengaged.
15. In a machine of the class described, the combination of a reciprocatory shoe structure, means for raising and lowering said shoe structure as a whole, and means for raising and lowering the lower part of said shoe structure independently of the upper part thereof.
20. In a machine of the class described, the combination of a shoe structure having an upper carriage part and a lower work engaging part, means for shifting the structure longitudinally as a whole, means for raising and lowering the structure as a whole, and means for independently raising and lowering said work engaging part.
25. In a machine of the class described, the combination of a rail, a shoe structure comprising an upper part and a lower part, said upper part receiving said rail whereby said shoe structure may be bodily reciprocated, means for vertically moving said rail and the entire shoe structure thereon, and means for vertically moving said lower part independently of said upper part and rail.
30. A longitudinally traveling shoe structure for machines of the class described comprising an upper section and lower work engaging section, means for vertically moving said shoe structure as a whole, and manually operable means for independently moving said lower work engaging part vertically, said manually operable means being adapted to reciprocally move said shoe structure longitudinally regardless of the relative vertical positions of the upper and lower sections thereof.
35. In a machine of the class described, the combination of a reciprocatory driver, a reciprocatory shoe structure comprising an upper part and a lower part, means for vertically reciprocating said shoe structure as a whole, a clutch member reciprocable in said lower part for controlling the connection and disconnection of said shoe structure relative to said reciprocatory driver, a link frame suspending said lower part from said upper part, an extension on said link frame, a lever pivoted on said extension to swing vertically and to move bodily, a connection between said lever and said clutch member for causing shifting of said clutch member when the lever is swung whereby to cause connection with or disconnection of said shoe structure from said reciprocatory driver, said lever serving also as a handle for operating said link frame to cause vertical adjustment of the lower part of the shoe structure independently of the upper part thereof.
40. In a machine of the class described, a longitudinally reciprocatory shoe structure comprising an upper part and a movable lower part, link members pivoted to said parts for assuring accurate vertical movement of the lower part, and a hand lever connected with said link members to control the swing thereof and thereby the adjustment of said lower part.
45. In a machine of the class described, the combination of a longitudinally reciprocable shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
50. In a machine of the class described, the combination of a longitudinally traveling shoe structure, said shoe structure comprising an upper part and a movable lower part, parallel links connecting said parts for assuring accurate vertical movement of said lower part, means tending to hold said lower part in upper position, and a hand lever structure connected with said links for controlling the swing thereof and thereby the adjustment of said lower part.
55. In a machine of the class described, the combination of a longitudinally traveling shoe structure, said shoe structure comprising an upper part and a lower part, a link frame suspending said lower part from said upper part, yielding mechanism acting on said link frame tending to hold said lower part normally in an upper position, and a hand lever connected with said link frame for controlling the movement thereof and thereby the adjustment of said lower part.
60. In a machine of the class described, the combination of a traveling driver, a shoe structure comprising an upper part and a lower part and supported to travel longitudinally, a link frame suspending said lower part from said upper part for vertical movement, extension walls on said link frame having longitudinal slots, a pivot bolt extending through said slots and between said walls, a lever extending between
65. In a machine of the class described, the combination of a traveling driver, a shoe structure comprising an upper part and a lower part and supported to travel longitudinally, a link frame suspending said lower part from said upper part for vertical movement, extension walls on said link frame having longitudinal slots, a pivot bolt extending through said slots and between said walls, a lever extending between
70. In a machine of the class described, the combination of a longitudinally reciprocating shoe structure comprising an upper part and a movable lower part, link members pivoted to said parts for assuring accurate vertical movement of the lower part, and a hand lever connected with said link members to control the swing thereof and thereby the adjustment of said lower part.
75. In a machine of the class described, the combination of a longitudinally reciprocating shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
80. In a machine of the class described, the combination of a longitudinally reciprocable shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
85. In a machine of the class described, the combination of a longitudinally reciprocating shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
90. In a machine of the class described, the combination of a longitudinally reciprocating shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
95. In a machine of the class described, the combination of a longitudinally reciprocating shoe structure comprising an upper part and a movable lower part, upper and lower parallel links connected between said parts for assuring accurate vertical movement of said lower part, and a lever structure connected with said lower links for controlling the swing of said links and thereby the adjustment of said lower part.
100. In a machine of the class described, the combination of a longitudinally traveling shoe structure, said shoe structure comprising an upper part and a movable lower part, parallel links connecting said parts for assuring accurate vertical movement of said lower part, means tending to hold said lower part in upper position, and a hand lever structure connected with said links for controlling the swing thereof and thereby the adjustment of said lower part.
105. In a machine of the class described, the combination of a longitudinally traveling shoe structure, said shoe structure comprising an upper part and a movable lower part, parallel links connecting said parts for assuring accurate vertical movement of said lower part, means tending to hold said lower part in upper position, and a hand lever structure connected with said links for controlling the swing thereof and thereby the adjustment of said lower part.
110. In a machine of the class described, the combination of a longitudinally traveling shoe structure, said shoe structure comprising an upper part and a lower part, a link frame suspending said lower part from said upper part, yielding mechanism acting on said link frame tending to hold said lower part normally in an upper position, and a hand lever connected with said link frame for controlling the movement thereof and thereby the adjustment of said lower part.
115. In a machine of the class described, the combination of a longitudinally traveling shoe structure, said shoe structure comprising an upper part and a lower part, a link frame suspending said lower part from said upper part, yielding mechanism acting on said link frame tending to hold said lower part normally in an upper position, and a hand lever connected with said link frame for controlling the movement thereof and thereby the adjustment of said lower part.
120. In a machine of the class described, the combination of a traveling driver, a shoe structure comprising an upper part and a lower part and supported to travel longitudinally, a link frame suspending said lower part from said upper part for vertical movement, extension walls on said link frame having longitudinal slots, a pivot bolt extending through said slots and between said walls, a lever extending between
125. In a machine of the class described, the combination of a traveling driver, a shoe structure comprising an upper part and a lower part and supported to travel longitudinally, a link frame suspending said lower part from said upper part for vertical movement, extension walls on said link frame having longitudinal slots, a pivot bolt extending through said slots and between said walls, a lever extending between
130. In a machine of the class described, the combination of a traveling driver, a shoe structure comprising an upper part and a lower part and supported to travel longitudinally, a link frame suspending said lower part from said upper part for vertical movement, extension walls on said link frame having longitudinal slots, a pivot bolt extending through said slots and between said walls, a lever extending between

- 5 said walls and receiving said bolt to be pivoted thereby on said walls, a clutch member reciprocable in said lower part, an abutment on said driving member, and a connection 6 between said clutch member and said lever whereby swing of said lever will cause shifting of said clutch member to position said member in or out of the path of the abutment on said driving member, swing of said 10 lever after shifting of said clutch member away from said driving member abutment causing swing of the link frame and vertical adjustment of the lower part of the shoe structure.
- 15 20. In a machine of the class described, the combination of a traveling driving member, a longitudinally traveling shoe structure comprising an upper part and a lower part, a link structure suspending said lower 20 part from said upper part for vertical movement, an extension on said link structure, a bolt extending through said extension and adapted to slide longitudinally thereon, a lever pivoted on said bolt to slide therewith, 25 a clutch abutment on said driving member, a clutch member shiftable on said lower part of the shoe structure, a connection between said clutch member and lever adapted to cause said clutch member to be shifted 30 into the path of the clutch abutment when said lever is swung into an upper position and adapted to withdraw said clutch member from the path of said abutment when said lever is swung to an intermediate position, locking surfaces on said lever adapted 35 to cooperate with said extension to lock said lever when in upper position and when in intermediate position, means tending to hold said lower part of the shoe structure in upper position during swing of the lever 40 between upper and intermediate position, said lever being adapted to be swung below intermediate position and serving then as a means for swinging said link structure to effect vertical adjustment of said lower part, 45 and means for holding said clutch member in unclutching position during such swing of the lever below intermediate position.
21. In a machine of the class described, the combination of a traveling member, a 50 traveling shoe structure comprising an upper part and a lower part, a structure hinged to said parts to suspend the lower part for vertical movement, a lever pivoted on said hinged structure to swing thereon to a vertical position or to an intermediate horizontal position, a clutch abutment on said driving member, a clutch member on said shoe structure, a connection between 55 said clutch member and lever for causing outward or inward shift of said member when said lever is swung to vertical or horizontal positions respectively, yielding means acting on said hinged structure and tending to hold said lower part in upper position 60 during swing of the lever between upper and intermediate positions, means for locking said lever to the hinged structure when in intermediate position whereby downward swing of said lever from horizontal position 65 70 will cause swing of the hinged structure and vertical adjustment of the lower part of the shoe structure.

In testimony whereof, I have hereunto set my hand.

CARL LAWRENCE MATTISON.
